delphia, Pa., a corporation of Delaware

Application January 25, 1937, Serial No. 67,278

Term of patent 14 years

To all whom it may concern:

Be it known that I, Reuben Robert Smith, a citizen of the United States, residing at Philadelphia, in the county of Philadelphia and State of Pennsylvania, have invented a new, original, and ornamental Design for a Drink Indicator, of which the following is a specification, reference being had to the accompanying drawing, forming part thereof.

Figure 1 is a front elevational view of the drink indicator embodying the design.

Figure 2 is a section taken on line 2—2 of Figure 1 looking in the direction of the arrows.

The printed matter appearing on the face of the drink indicator does not form a fixed and permanent feature of the design, but is variable in nature, and merely illustrative.

I claim:

The ornamental design for a drink indicator as shown and described.

REUBEN ROBERT SMITH.
